CLAIM

The ornamental design for a lampholder, as shown and described.

DESCRIPTION

This application is related to co-pending applications: Ser. No. 11/322,837, filed Dec. 30, 2005 and titled “Halo Flex Track”; Ser. No. 11/324,099, filed Dec. 30, 2005 and titled “Halo Power Supplies”; Ser. No. 11/323,231, filed Dec. 30, 2005 and titled “Halo Clam Shell Connections”; and Ser. No. 11/323,755, filed Dec. 30, 2005 and titled “Halo Hubs and Connections”.

FIG. 1 is a top perspective view of a first embodiment of a lampholder showing my new design;

FIG. 2 is a bottom perspective view thereof;

FIG. 3 is a front view thereof, the rear view being identical;

FIG. 4 is a left side view thereof, the right side being identical;

FIG. 5 is a top view thereof;

FIG. 6 is a bottom view thereof;

FIG. 7 is a top, front perspective view of a second embodiment thereof;

FIG. 8 is a bottom, front perspective view thereof;

FIG. 9 is a front view thereof, the rear view being identical;

FIG. 10 is a left side view thereof, the right side view being identical;

FIG. 11 is a top view;

FIG. 12 is a top perspective view of a third embodiment thereof; and,

FIG. 13 is a bottom perspective view thereof.

The broken lines form no part of the claimed design.
